UNITED STATES PATENT OFFICE.

ROBERT E. DICKINSON, JR., OF MEMPHIS, TENNESSEE.

GOLF-CLUB SHAFT.

Application filed January 24, 1927. Serial No. 163,102.

Golf club shafts as now manufactured from wood, are not uniform as to weight, flexibility, elasticity, torsion and strength, and moreover are subject to warping, particularly when used in damp air on the green and then subjected to dry air in the club house.

It is the primary object of my invention to provide novel means whereby these difficulties may be overcome, and I attain this end by providing a shaft turned from a single solid piece of hard wood such as hickory and provided with a longitudinal bore in which a spring metal tube is snugly held. By placing tubes of varying lengths, thickness and resiliency in shafts having non-uniform characteristics, selecting the proper tube for each shaft, their shortcomings may be corrected, and the completed shafts made substantially uniform as to weight, flexibility, elasticity, torsion and strength, and it is worthy of note that the external uniformity of the wood, is not disturbed but remain the same as in a first class all-wood shaft.

A tube having its interior unoccupied tends to produce an undesirable sound and has a tendency to jerk the player's hands when striking a ball, and hence I prefer to provide a filler for said tube which will overcome these tendencies. Moreover, under a great amount of flexure, a tube with its interior empty, will change its cross sectional shape and tend to flatten. Such change of shape is necessarily imparted to the surrounding wood, with a tendency to split the same. A further aim of the invention however is to utilize a hard wood filler in the tube which will minimize its tendency to flatten under excessive flexure and hence will overcome the liability of splitting the shaft. It will also be observed that by using the same kind of wood for the shaft body and the tube filler, the advantageous characteristics of the all-wood shaft are maintained, yet the deficiencies thereof are corrected by the spring metal tube.

The invention will be specifically described with reference to the accompanying drawing, in which:—

Figs. 1, 2 and 3 are sectional views partly in elevation showing different stages in the manufacture of one of the club shafts.

Fig. 4 is a transverse sectional view on line 4—4 of Fig. 3.

Fig. 5 is a view similar to Fig. 2 but

showing the club head and the shaft connected.

Fig. 6 is a view similar to Fig. 2, but showing a somewhat modified construction. 60

Fig. 7 is a transverse section on line 7—7 of Fig. 6.

In carrying my invention into effect, I first take a length of hickory doweling 8 and form a bore 9 in its axial portion and of a length determined by the characteristics to be imparted to the completed shaft and by the kind of club head with which it is to be used. Next, a length of hickory doweling 10 is forced tightly into the spring 70 steel tube 11 which has been selected for use, and this tube 11 with the doweling 10 therein, are tightly forced into the bore 9, being of such length as to terminate somewhat above the lower end of said bore. 75 The unoccupied portion of the bore is then plugged by a short piece of hickory doweling 12. Now, the entire assemblage is placed in a lathe and turned to the desired shape, as disclosed in Fig. 3. The finished shaft is 80 then secured in the socket 13 of the club head 14, in the usual manner, and it will be observed from Fig. 5, that the tube 11 and the doweling 10 are of a length to extend into the socket 13 preferably about one inch 85 so as to reinforce the shaft against breakage at the open end of said socket.

If desired, instead of using the plain tube 11 shown in Figs. 1 to 5, I may make use of a tube 11^a having a sharp longitudinal ridge 90 or key at its exterior. This ridge or key tightly embeds in the surrounding wood, when the tube is being forced into the bore 9, and thus tightly anchors the tube in place. Moreover, by connecting the tube with the 95 wood in this manner, torsional strain upon the former is transmitted also to the tube.

When the ridge or key 11^b is employed, it is preferably formed by outwardly bending one edge of the sheet of steel, from which the tube is formed, as will be clear from Fig. 7.

By employing the novel construction shown and described, or a substantial equivalent thereof, a golf shaft is produced having the advantageous characteristics hereinbefore enumerated.

I claim:

1. A golf club shaft comprising a single solid piece of wood turned to shape and formed with a central longitudinal bore, 110 which opens through its lower end, a spring

- metal tube snugly held in said bore and terminating a short distance from the lower end thereof, a wood dowel snugly fitted into said tube, and a second wood dowel snugly fitted into the lower portion of the bore and abutting the lower ends of said tube and the first named dowel, said tube extending into the portion of the shaft for reception in the usual socket of the club head.
10. 2. A golf club shaft comprising a single solid piece of wood turned to shape and formed with a central longitudinal bore, and a one-piece spring metal tube snugly

received in said bore, said tube and the wood providing for the requisite flexibility, elasticity, torsion, weight and strength of the club and producing an article whose external uniformity is identical with an all-wood shaft, said tube being provided with an external longitudinal key embedded in the wood and securely anchoring said tube in place.

In testimony whereof I have hereunto affixed my signature.

ROBERT E. DICKINSON, JR.
